POCKET TYPE CIGARETTE EXTINGUISHER

Henry P. Hoffman, Preston, Iowa

Application October 4, 1937, Serial No. 167,276

3 Claims. (Cl. 206—41)

The present invention relates to smokers' accessories and appliances and has more particular reference to a novel pocket type cigarette extinguisher and ash receiver.

As implied by the preceding general statement of the invention, I am sufficiently conversant with the prior state of the art to realize that cigarette snuffers, extinguishers and pocket ash receivers are not broadly new. Hence, in setting out to perfect the preferred embodiment of my improved conception, I have developed what is perhaps a specific structural novelty in this particular line of endeavor in that it is characterized by certain appreciable refinements and improvements.

To be more specific, in accordance with my objective I have found it expedient as well as practicable to adopt for use a simple lid equipped box or casing, this having therein a cigarette receiver and satisfactorily usable nipper means for severing the lit end of the cigarette.

Other features and advantages exemplified as embodied in this nipper equipped magazine style accessory will become more readily apparent from the following description and drawings.

In the drawings:

Figure 1 is a perspective view of a device constructed in accordance with the principles of the present inventive idea.

Figure 2 is a longitudinal sectional view showing the internal details to advantage.

Figure 3 is a view like Fig. 2 illustrating the relative relationship of parts when the tip severing or nipper means is actuated.

Figure 4 is a horizontal longitudinal section on the line 4—4 of Fig. 3.

Figure 5 is a fragmentary transverse section on the line 5—5 of Fig. 2.

Figures 6 and 7 are perspective drawings of certain of the details.

The device as a single object may be visualized as comprising a miniature pocket size box or casing 8. It is made of suitable material and includes a body or receptacle portion 9 and a lid 10 hinged at 11 and provided with a keeper clip 12.

One end of the casing is apertured and here I provide a closing disk 13, this being pivoted as at 14 and constituting a closure for the outer end of a horizontal tube 15 constituting a receiver into which the cigarette is projected. The inner end of the tube, which is open, is suitably suspended in a hanger bracket or fixture 16. Coordinated with the severing end of the tube 15 is a U-shaped bracket 17 which constitutes a

sort of a stirrup for the ignited end of the cigarette. Cooperating with the stirrup, in which the cigarette is saddled, is an arcuate flat spring 18.

The nipper is indicated in Fig. 6 and denoted 5 by the numeral 19. It comprises an operating stem 20 having a finger piece 21 and a head 22 forming the cutting blade. The blade is preferably spear-shaped and provided with a marginal cutting edge 23 so that it penetrates the 10 cigarette and sweeps down through it in an effective severing or cutting action. The nipper is normally maintained in the elevated position shown in Fig. 2 by way of a return spring 24 anchored in the casing and having its free end extending through a slot 25 in the cutting blade. The nipper may be held in its inward position by placing a notch in the outer end of the stem 20 in engagement with a wall of the slot in an edge wall of the casing through which the stem 20 passes. When in this position, the nipper will not interfere with the placing of the device in a pocket, and when in this position, the blade of the nipper will close the inner end of the tube 15, thus holding a cigarette or a cigarette butt in 25 said tube, and said blade will also act to prevent ashes from the interior of the casing from getting in the tube with the butt. Thus the butt is kept clean and may be re-lighted and smoked, if desired. The cutting blade also carries a 30 rigid yoke 26 and this slidably embraces the arcuate spring 18. Hence, as the knife is depressed so to speak against the tension of the spring 24, the yoke sweeps down in cam pressure contact with the spring 18. This flexes the spring 35 into the position seen in Fig. 3. Thus the action of the knife is properly guided and the spring is brought into a position to serve as a stop or abutment for the ignited end of the cigarette. The spring 24, when in the position shown in 40 Figure 3, also acts to extinguish the lighted end of the cigarette. It is evident therefore that in this way the lit end of the cigarette is severed conveniently and allowed to drop down into the depository.

Not only does the device serve as a severing extinguisher for cigarettes, but it comes in as a handy appliance for a place for ashes when an ash tray, of the regular type, is not handy. Then, too, it constitutes an effective depository for 45 cigarette butts.

It is thought that persons skilled in the art to which the invention relates will be able to obtain a clear understanding of the invention after considering the description in connection 55

with the drawings. Therefore, a more lengthy description is regarded as unnecessary.

Minor changes in shape, size, and rearrangement of details coming within the field of invention claimed may be resorted to in actual practice, if desired.

What is claimed is:

1. A device of the class described comprising a casing, a cigarette receiving tube in said casing and having one end opening out through a wall of the casing, a door for closing said end, a U-shaped stirrup supported in the casing and having its bight located in alignment with the tube and spaced from the inner end thereof, a knife including a stem and a blade, another wall of the casing having a slot therein through which the stem passes, said blade entering the space between the stirrup and the inner end of the tube when the stem is pressed inwardly, a spring for normally holding the blade and stem in their outward position, and means for holding the stem and blade in their inward position and against the action of the spring.

2. A device of the class described comprising a casing, a tube supported in the casing and having one end opening out through a wall of the casing, a cutting member including a blade and a stem, another wall of the casing having a slot therein through which the stem passes, said cutting member being arranged at rightangles to the tube, with the blade extending across the inner end of the tube when the stem is forced inwardly, a spring member having one end connected with that wall of the casing having the slot therein, and said member having a part spaced from the inner end of the tube with the

cutting member located between the spring member and the tube, and a yoke connected with the cutting member and passing around the spring member for forcing the spring member toward the tube when the cutting member is forced inwardly. 5

3. A device of the class described comprising a casing, a tube supported in the casing and having one end opening out through a wall of the casing, a cutting member including a blade 10 and a stem, another wall of the casing having a slot therein through which the stem passes, said cutting member being arranged at rightangles to the tube, with the blade extending across the inner end of the tube when the stem is forced 15 inwardly, a spring member having one end connected with that wall of the casing having the slot therein, and said member having a part spaced from the inner end of the tube with the cutting member located between the spring member and the tube, a yoke connected with the cutting member and passing around the spring member for forcing the spring member toward the tube when the cutting member is forced inwardly, and a U-shaped stirrup connected to the 20 slotted wall of the casing and having its bight part spaced from but in alignment with the tube and between which and the inner end of the tube the knife member operates, said stirrup member being located between the knife member and the spring member, the spring member being pressed against the bight part of the stirrup when pressed by the yoke member of the knife member. 25
